UNITED STATES PATENT OFFICE.

RALPH L. MORGAN, OF WORCESTER, MASSACHUSETTS.

GAS-PRODUCER.

No. 901,359.

Specification of Letters Patent.

Patented Oct. 20, 1908.

Application filed August 7, 1905. Serial No. 272,962.

To all whom it may concern:

Be it known that I, RALPH L. MORGAN, a citizen of the United States, residing at Worcester, in the county of Worcester and Commonwealth of Massachusetts, have invented a new and useful Improvement in Gas-Producers, of which the following is a specification, accompanied by drawings forming a part of the same, in which—

10 Figure 1 represents a central vertical sectional view of the lower portion of a gas producer embodying my invention. Fig. 2 is a top view of the fuel agitating blades, and Fig. 3 is a transverse sectional view on line 3—3, Fig. 2.

15 The objects of my invention are to provide means for agitating the mass of fuel in the gas producing chamber, whereby the mass of fuel is rendered homogeneous in 20 the zone of combustion, and the formation of air flues or "pipes" is prevented; to regulate the discharge of ashes from the gas producing chamber; to provide means for water sealing the lower end of the gas producing 25 chamber; to control the distribution of air to the fuel; to provide means for actuating the operative parts of the mechanism and in general to increase the efficiency of the gas producer both as relates to quantity and 30 quality of the product; and I accomplish these objects by the construction and arrangement of parts as hereinafter described and pointed out in the annexed claims.

Referring to the accompanying drawings 35 1 denotes the gas producing chamber inclosed within walls 2 and provided at its lower end with a hopper shaped extension 3 terminating in a spout 4, through which the ashes are delivered from the gas producing chamber. The inclosing walls 2 and hopper 3 are supported upon legs 5, 5, resting upon a horizontal framework 6 which is supported upon masonry 7 in which is formed an ash pit 8 having converging sides 40 9, 9. Journaled in a bearing 10 supported by the framework 6 is a hollow rotating spindle 11 carrying near its lower end an annular gear 12 in mesh with a pinion 13 upon a rotating shaft 14. Attached to the 45 spindle 11 and above the bearing 10 is a water pan 15 with its upper edge 16 some distance above the lower end 17 of the spout 4. Water is supplied to the pan 15 through a water pipe 18, thereby water sealing the 50 spout 4. The upper end of the hollow rotat-

ing spindle 11 is provided with a cone shaped cup 19, from diametrically opposite sides of which extend blades 20, 20, which are rotated in the direction of the arrows 21, 21, Fig. 2. Each of the blades 20, 20, consists 60 of an oblique section 22 on the advancing side of the blade, and with a narrow depending lip 23 on the retreating side of the blade. As the blades 20 are rotated in the direction of the arrows 21, 21; through the mass 65 of incandescent fuel, the fuel is lifted vertically by the oblique section 22 of the blade, and as the blade passes the fuel falls downward over the depending lip 23.

The agitation of the fuel by the revolving 70 blades 20 breaks up any masses which may be formed by the coking of the coal, fills up any flues or pipes formed in the mass of fuel, and renders the entire mass of fuel 75 homogeneous, causing a uniform combustion to be maintained throughout the gas producing chamber.

A blast of steam or air is admitted under 80 pressure through a pipe 24 to the lower end of a hollow rotating spindle 11 which is discharged to the upper end of the spindle through openings 25, 26. The air escaping through the openings 26 is admitted directly beneath the under side of the blades 20 which, passing radially outward, escapes 85 into the mass of fuel around the lower edge 27 of the depending lip 23, where it is admitted into the mass of falling fuel as it falls over the retreating edge of the rotating blades, thereby admitting a supply of 90 oxygen to the disturbed fuel immediately at the rear of the rotating blades. By this distribution of the air around the edge of the depending lip 23, the combustion of fuel is restored which may have been partially 95 checked by the agitation of the blades 20, 20. The ashes formed by the combustion of fuel descends through the hopper 3 and spout 4 into the water pan 15 and, overflowing the water pan, descends into the ash pit 8 from 100 the bottom or apex of which they may be removed by any convenient method, such for example, as a traveling chain or rope 28 carrying at intervals disks 29.

The gears 12 and 13 are protected by a 105 cover 30. The flow of ashes from the hopper 3 into the water pan 15 is regulated by a telescopic sleeve 31 inclosing the spout 4 and suspended upon chains 32 which are attached to the top of the sleeve 31 and fas- 110

tened to pins 33 by which the sleeve 31 is vertically adjusted, being lowered to check the flow of ashes into the pan 15.

What I claim as my invention and desire to secure by Letters Patent is:—

1. The combination with a combustion chamber, of a rotating spindle coaxial with said chamber, and a radial blade carried by said spindle, said blade consisting of an 10 oblique section on its advancing side and a narrow depending lip on the retreating side of the blade.

2. In a gas producer, the combination with an ash receptacle, of a rotating spindle 15 extending above said ash receptacle, a blade carried by said spindle approximately at right angles thereto, said blade provided with a flange depending from the blade at an oblique angle thereto upon its forward 20 side and a vertical depending flange upon the rear side of said blade, and means for rotating said spindle.

3. In a gas producer, the combination with a combustion chamber, of a rotating 25 vertical spindle extending into the zone of combustion in said chamber, and an inverted trough shaped blade carried by said spindle approximately horizontal and transverse to said chamber, whereby the incan-

descent coal in said chamber is given a vertical movement as the blade rotates.

4. In a gas producer, the combination with a combustion chamber, of a hollow vertical rotating spindle extending into the zone of combustion in said chamber, an angular blade approximately horizontal, whereby the incandescent coal in said chamber is given a vertical movement, and means for supplying air through said spindle beneath said blade, arranged to contact with the coal as it drops from said blade.

5. In a gas producer, the combination with a combustion chamber, of a rotating vertical hollow spindle extending into the zone of combustion having openings at its 45 top for the escape of air, a hood carried by said spindle arranged to cause the horizontal movement of the air from said spindle, and an approximately horizontal blade carried by said hood and extending from its periphery transversely through the incandescent coal in said chamber.

Dated this 31st day of July 1905.

RALPH L. MORGAN.
